UNITED STATES PATENT OFFICE.

BURTON D. KNICKERBOCKER, OF CHICAGO, ILLINOIS.

BATH-BRUSH WITH DETACHABLE HANDLE.

No. 823,471.

Specification of Letters Patent.

Patented June 12, 1906.

Application filed December 31, 1903. Serial No. 187,375.

To all whom it may concern:

Be it known that I, BURTON D. KNICKERBOCKER, a citizen of the United States, residing at Chicago, in the county of Cook and State of Illinois, have invented a certain new and useful Improvement in Bath-Brushes with Detachable Handles, of which the following is a full, clear, concise, and exact description, reference being had to the accompanying drawings, forming a part of this specification.

My invention relates to an improved bath-brush with a detachable handle.

In Letters Patent No. 666,759, issued January 29, 1901, I have described a bath-brush made of rubber and containing an interior chamber adapted to be connected with a suitable source of water-supply and carrying upon its face a series of teeth, said teeth having ducts formed therein extending from said interior chamber through the teeth, said teeth constituting the scrubbing-surface of the brush.

The present invention relates to a brush of this general type provided with a detachable handle. It will be understood, however, that my improved handle may be used with other forms of brush than that above described.

The object of my invention is to provide a handle which will securely hold the brush when being used therewith and which can be readily detached therefrom when it is desired to use the brush with the handle removed.

Referring to the drawings, in which the same reference characters indicate similar parts throughout the several figures, Figure 1 is a plan view of my improved brush-holder with the brush in position. Fig. 2 is a sectional view on the line 2 2 of Fig. 1. Fig. 3 is an end view of the holder and brush. Fig. 4 is a sectional view showing the manner of attaching the brush and the handle. Fig. 5 is the same as Fig. 4 with the handle removed. Fig. 6 is a plan view of a portion of the handle, showing the supply-tube in dotted lines; and Fig. 7 is a perspective view of the connection for attaching the supply-tube to the brush.

Referring now to the drawings by reference characters, my improved handle 1 consists of a back 3 and a handle proper, 4, attached thereto in any suitable manner, preferably by screws 5. The back 3 is preferably made of flexible material, and to impart additional flexibility thereto a portion thereof may be cut away, as

shown in Fig. 1; but this is not essential, the back being made rigid, if desired. The back 3 carries studs 6, which are secured thereto preferably by nuts 7, said studs being formed with enlarged ends 9. Any suitable projection may be provided upon the back 3 in lieu of said studs.

The brush 10 has a duct 11, communicating with an interior chamber 12, adapted to be connected by a tube 13 and faucet connection 14 with a suitable source of water-supply and carries a series of teeth 15, having ducts 16, formed therein for conveying the contents of the chamber 12 to the scrubbing-surface of the brush. Formed, preferably, upon the ends of the brush are lugs or ears 17, having apertures 18 formed thereon, said apertures being formed with irregular bores 19, adapted to hold the lugs or ears 17 in firm engagement with the studs 6, carried by the back 3 of the holder 1. While I prefer to form lugs or ears upon the brush, as above described, such construction is not essential, and any suitable form of projection thereon or any suitable form of aperture therein may be adapted in lieu of the lugs or ears described. To give a greater degree of resiliency to the brush, I prefer to mount same so as to leave a space between the brush and the back piece 3 of the handle, as shown in Figs. 2 and 4.

One end of the tube 13 is attached to a coupling 20, which extends through the duct 11, formed in the brush, and communicates with the interior chamber 12. It has been found desirable in practice to provide means for distributing the water admitted through the duct 11 in equal quantities over the entire interior of the chamber 12 in order to produce a uniform flow through the ducts 16 in the teeth 15 of the brush. Otherwise the water has been found to collect in the end of the brush farthest from the duct 11 and to flow in larger quantities through the ducts 16 located at that end of the brush than through the ducts at the other end of the brush. I prefer to accomplish this result by providing a projection 21 upon the coupling 20, said projection having a series of holes 22 formed therein, as shown in Fig. 7. It will be understood, however, that the form of the projection 21 is not essential, as the end of the coupling might be formed in many different ways and carry differently-formed openings to accomplish the same result.

The handle proper, 4, is preferably curved

2

to permit the tube 13 to pass through the same, and I prefer to curve the edges 23 of the handle 4 to normally inclose the tube 13 and permit the tube to be inserted in and removed from the handle between the curved edges thereof, as shown in Fig. 6. I do not wish to limit myself to the particular construction of the handle described, as other forms of handle might be used with or without the tube passing therethrough, and other means might be adapted for retaining the tube in and removing the same from the handle.

15 While I have described my invention with particular reference to the details of construction, I do not wish to be understood as limiting myself to such details.

I am aware that many changes might be made in the details of construction without departing from the spirit of my invention, and I therefore claim the right to make such modifications as fairly fall within the scope of my invention.

Having described my invention, what I
25 claim as new, and desire to secure by Letters
Patent, is—

1. In combination, a brush having a flexible back and teeth formed upon said back, said back being hollow and provided with interscstices, a tube connected to said back, a frame attached to said flexible back and supporting the same, and a handle mounted upon said frame.

2. In combination, a brush having a flexible back and teeth formed upon said back, said back being hollow and provided with interstices, a tube connected to said back, a frame attached to said flexible back and supporting the same, and a tubular handle mounted upon said frame, said tube being arranged within said handle.

3. In combination, a brush having a flexible back and teeth formed upon said back, said back being hollow and provided with in-

terstices, a tube connected to said back, a 45 frame attached to said flexible back and supporting the same, and a tubular handle mounted upon said frame, and provided with a longitudinal slit, said tube being arranged within said handle and adapted to pass 50 through said slit to place the same within the handle and remove the same therefrom.

4. In combination, a brush having a flexible back and teeth formed upon said back, said back being hollow and provided with interstices, a tube connected to said back, a frame supporting said brush, means attaching said frame to said flexible back and capable of permitting said brush to be readily detached from said frame, and a tubular handle mounted upon said frame. 55 60

5. In combination, a brush having a flexible back and teeth formed upon said back, said back being hollow and provided with interstices, a tube connected to said back, a frame supporting said brush and provided with studs, said studs being placed in holes formed in said back to connect said brush to said frame, and a handle mounted upon said frame. 65 70

6. In combination, a brush having a flexible back and teeth formed upon said back, said back being hollow and provided with interstices, a tube connected to said back, a frame supporting said brush, means attaching said frame to said flexible back and capable of permitting said brush to be readily detached from said frame, and a tubular handle mounted upon said frame, said tube being arranged within said handle. 75 80

In witness whereof I have hereunto subscribed my name in the presence of two witnesses.

BURTON D. KNICKERBOCKER.
